US0D1053488S

(12) **United States Design Patent** (10) **Patent No.:** **US D1,053,488 S**
(45) **Date of Patent:** **** Dec. 3, 2024**

(54) **SCREEN CLEANER**

(71) Applicant: **Chengwen Zeng**, Yiwu (CN)
(72) Inventor: **Chengwen Zeng**, Yiwu (CN)
(**) Term: **15 Years**
(21) Appl. No.: **29/895,171**
(22) Filed: **Jun. 19, 2023**
(51) LOC (14) Cl. **07-05**
(52) U.S. Cl. **USPC D32/35**
(58) **Field of Classification Search**
USPC D26/72, 75; D32/1, 35
CPC A47L 9/20; A47L 11/4033; A47L 25/005
See application file for complete search history.

(57) **CLAIM**

The ornamental design for a screen cleaner, as shown and described.

DESCRIPTION

FIG. 1 is a first perspective view of a screen cleaner showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof; and,

FIG. 9 is an exploded view of the screen cleaner thereof. The broken lines shown in the drawings depict portions of the screen cleaner that form no part of the claimed design.

1 Claim, 9 Drawing Sheets
